[57] CLAIM

The ornamental design for a rear combination lamp for an automobile, as shown and described.

DESCRIPTION

FIG. 1 is a front perspective view of a rear combination lamp for an automobile showing my new design; FIG. 2 is a front elevational view thereof; FIG. 3 is a rear elevational view thereof; FIG. 4 is a top plan view thereof; FIG. 5 is a bottom plan view thereof; FIG. 6 is a left side elevational view thereof; FIG. 7 is a right side elevational view thereof; and FIG. 8 is a front perspective view of a second embodiment of my new design, the second embodiment being identical to the first embodiment except for the contrast on the front surface of the lens.
